John C. Shaw's
Improvement in
Rubber Traction for condensing Carding Engines

73760

Inventor

United States Patent Office.

JOHN C. SHAW, OF MANAYUNK, PENNSYLVANIA.

Letters Patent No. 73,760, dated January 28, 1868.

IMPROVEMENT IN CONDENSING-CARDING MACHINES.

The Schedule referred to in these Letters Patent and making part of the same.

TO ALL WHOM IT MAY CONCERN:

Be it known that I, JOHN C. SHAW, of Manayunk, county of Philadelphia, and State of Pennsylvania, have invented a certain new and useful Improvement in Rubber-Motions for Condensing-Carding Engines; and I do hereby declare that the following is a full, clear, and exact description of the construction and operation of the same, reference being made to the annexed drawings, which make a part of this specification, in which—

Figure 1 is a side view.

Figure 2 is an end view.

Figure 3 is a view of the steel plate.

Figure 4 is a view of the top plate

Similar letters in the drawings represent the same parts.

The nature of my invention consists in the combination and arrangement of a steel plate and set-screw, for the purpose of taking up the "loose motion" in the "rubber-motion" of a condensing-carding engine.

To enable others skilled in the arts to make and operate my improvement, I will describe the construction and operation of the same.

A represents one of the rubbing-roller stands, which is constructed in the usual manner, with the exception of the part marked *a*, which is constructed as shown in the drawings. C is a section of one of the rubbing-roller shafts. D represents a collar on the end of the roller-shaft C. The part of the stand marked *a* has a hole drilled through it, and into this hole is screwed the set-screw E. The cast-steel plate B is fitted to the part *a*, and of such a height that the end of the plate B will strike the centre of the collar on the shaft C. The plate B has a slot, *f*, in it to admit adjusting. The stand A is fastened to the frame of the "rubber-motion" by a bolt through the slot *g*.

The operation is as follows: The "rubber-motion" receives a rapid reciprocating motion, and it is necessary to keep the collar D close up to the stand A, to prevent jarring and noise. The plate B is moved up until it touches the collar D. It is then made fast by the set-screw E, but not so tight as to prevent the roller from revolving. As the collar D and the end of the plate wear away the slot in the plate permits it to be adjusted, and prevents any noise or jarring.

This improvement has several advantages over the old plan of the pointed set-screw and jam-nut. In case the roller laps, the pointed set-screw will prevent the roller from rising, and will cause the roller-shaft to bend, or is liable to tear off the covering from the roller. There is another difficulty. It is necessary to take out the rubbing-roller to grind the doffers, and with the pointed set-screw and jam-nut it is necessary to screw out the set-screw in order to get the rollers out. With my improvement it is not necessary to move the plate B, and the rollers can be lifted in and out; and in case of a lap forming on the rollers freely they are free to rise, and prevent any injury to them.

Claim.

In combination with the collar D of the roll C and bracket A, I claim the slotted plate B and set-screw E, substantially as and for the purpose set forth.

JOHN C. SHAW.
